UNITED STATES PATENT OFFICE

144,741

DESIGN FOR A COMBINED DISPLAY STAND AND MERCHANDISE CONTAINER UNIT

Harry Steinberg, New York, N. Y.

Application October 5, 1945, Serial No. 122,556

Term of patent 14 years

(Cl. D80—9)

To all whom it may concern:

Be it known that I, Harry Steinberg, a citizen of the United States of America, residing in New York city, county of New York, and State of New York, have invented a new, original, and ornamental Design for a Combined Display Stand and Merchandise Container Unit, of which the following is a specification, reference being had to the accompanying drawing, forming part thereof, wherein the figure is a front perspective view of a combined display stand and merchandise container unit showing my new design.

I claim:

The ornamental design for a combined display stand and merchandise container unit, substantially as shown.

HARRY STEINBERG.
